(57) **CLAIM**

The ornamental design for a coffee grinder, as shown and described.

DESCRIPTION

FIG. 1 is a perspective view of a coffee grinder, shown with the lid components removed for ease of illustration;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view of the lid components of the coffee grinder, shown removed for ease of illustration;
FIG. 10 is another perspective view thereof;
FIG. 11 is a front elevational view thereof;
FIG. 12 is a rear elevational view thereof;
FIG. 13 is a left side elevational view thereof;
FIG. 14 is a right side elevational view thereof;
FIG. 15 is a top plan view thereof;
FIG. 16 is a bottom plan view thereof;
FIG. 17 is a perspective view of the coffee grinder where a first lid is assembled with the grinder;
FIG. 18 is a perspective view of the coffee grinder where a second lid is assembled with the grinder;
FIG. 19 is a perspective view of the coffee grinder where the second lid is assembled with a grinder body of the grinder;
FIG. 20 is an exploded perspective view of the coffee grinder; and,
FIG. 21 is an exploded perspective view of the coffee grinder where the first lid is assembled with a bottom cup of the grinder.
The broken lines in the drawings depict portions of the coffee grinder that form no part of the claimed design.

1 Claim, 21 Drawing Sheets
